UNITED STATES PATENT OFFICE

2,570,661

ECONOMIZER UNIT

Claud W. Gray, El Paso, Tex.

Application January 16, 1950, Serial No. 138,850

5 Claims. (Cl. 123—127)

1

This invention relates to novel and useful improvements in internal combustion engines and attachments therefor.

An object of this invention is to improve the operation of an engine with relation to the efficiency of operation of that engine by controllably introducing a low grade fuel into the intake manifold of the engine in response to the temperature of the engine.

This is accomplished by employing a thermostat in an attachment. The thermostat is disposed in the line of travel of a current of bypassed engine coolant so that when the engine coolant is sufficiently warm or hot, the thermostat is operated thereby opening one valve and closing the other, these valves being operated directly by the thermostat. Moreover, the valves are arranged to control the inlet of high grade and low grade fuel into the carburetor or intake manifold of the engine.

Ancillary objects and features will become apparent in following the description of the illustrated forms of the invention.

In the drawings:

Figure 1 is a side view of a typical engine having the device applied in one suggested manner of attachment;

Figure 2 is a top view of the attachment with a portion broken away in section to illustrate detail of construction;

Figure 3 is a sectional view taken substantially on the line 3—3 of Figure 2 and in the direction of the arrows; and

Figure 4 is an enlarged detail view taken in section and showing a modification of the valve arrangement for the high and low grade fuel.

An engine generally indicated at 10 is provided with the usual appurtenances contiguous to an engine such as a water pump 12 and the carburetor 14. A fuel pump 16 having a line 18 attached thereto is secured to the engine. This line connects with an unshown tank which is adapted to hold a low grade fuel. A conduit 20 extends from the other side of the fuel pump 16 and terminates in communication with a passage 22 formed in the unit disclosed in Figure 3.

A second fuel pump 24 is secured for operation to the engine and has a line 26 extending from an unshown tank which is adapted to accommodate high grade fuel. The line 28 extending from the opposite side of the fuel pump 24 terminates in communication with a passage 30 formed in the unit disclosed in Figure 3.

A heated water inlet conduit 32 is secured in communication with the water jacket of the en-

2

gine, as by a nipple connection with the head, and terminates in communication with the passage 34 (Figure 3). A water line 36 is connected with the passage 38. The line 36 is attached to the water pump 12 so as to form a by-pass circuit for the coolant of the engine. A valve 40 is supplied in the passage 38 and has a control handle 42 secured thereto. A push-pull link 44 is secured to the valve handle 42 in order to operate the valve 40. The purpose of the valve is to allow manual closing of the by-pass coolant circuit including the conduit 32 and 36, respectively, just prior to turning off the engine. By this expedient, the thermostat 46 is allowed to cool where-
15 by the high grade fuel is introduced into the bowl of the carburetor rather than the low grade fuel on which the engine was operating. Accordingly, after the engine is stopped, the carburetor bowl is supplied with high grade fuel for facility of
20 again starting the engine. This operation will be more fully detailed subsequently.

The device consists of a case or housing 50 with a cover 52 screwed thereon. The case or housing has passages 38 and 34 formed therein, 25 while the cover 52 has a diaphragm 54 separating it from the lower part of the case 50. The diaphragm divides the interior of the case into a fuel chamber 56 and a water chamber 58.

A flange 60 extends interiorly of the case 50 and forms a seat for the hanger 62. The hanger accommodates the thermostat 46. This thermostat has an operating shank 66 protruding from the upper part thereof and secured to the dia-
30 phragm 54. A valve block 68 is also secured to the operating shank 66 so that when the dia-
35 phragm expands or contracts, this movement is transmitted directly to the valve block 68.

The hanger 62 is secured by means of a screw 69 to the lower part of the case 50. A drain cock 70 is disposed at the lower part of the liquid chamber 58 and is carried by the casing 50.

The passage 32 has a spring 74 therein which constantly presses the ball-type valve 76 in the V-shaped notch 78 formed in one face of the valve block 68. The passage 30 has a spring 80 disposed therein which constantly presses the ball-type valve 82 against an inclined face 84 which forms part of a notch 86 in the valve block 68.

A bonnet 84 is disposed on a nipple 86 which rises from the cover 52. The nipple forms a part of the valve chamber for the valve block 68. A stem 88 is disposed in the bonnet 84 and is held in place by means of a fluid-tight seal 90. The 50 function of the valve stem 88 is to limit the travel

of the block 68 and also to override the function of the thermostat 46 in case of emergency or whenever desired, by simply turning the handle 92 and threading the stem 88 downwardly to press against the block 68.

Reference to Figures 1 and 2 shows a conduit 94 communicating with the passage 95, said passage 95 being in direct communication with the valve chamber formed around the block 68.

The operation of this form of the invention is as follows: High grade fuel is pumped by means of the fuel pump 24 into the chamber 56. This fuel passes through the passage 95, the conduit 94 and then to the bowl of the carburetor so that the engine may be operated. However, when the engine reaches a predetermined temperature, this high grade fuel is not employed and fuel entering the passage 22 and the fuel chamber 56 passes through the passageway 95 and into the carburetor.

In order to make the change-over, the liquid coolant of the engine is permitted to pass through the by-pass system including the chamber 58, the conduit 32 and the conduit 36. The valve 40 is in the open condition at this time. Inasmuch as the water is passing through this chamber and the thermostat 46 is therein, when the water temperature increases, the thermostat will expand whereby the valve block 68 will move upwardly. This will cause the ball 76 to close the passage 30 which normally conducts a high grade fuel. At this time the ball 82 is pressed by means of the spring into the notch 86 inasmuch as the valve block 68 has moved upwardly. This allows low grade fuel to enter the carburetor in lieu of the high grade fuel.

Shortly before the engine is to be stopped, the valve 40 is turned thereby cutting off the coolant by-pass system of the engine for the purposes detailed previously.

Reference is now made to Figure 4. This embodiment of the invention differs from the described one in the means of sealing and opening the high and low grade fuel passageways 100 and 102, respectively. The diaphragm 54 is illustrated together with a portion of the thermostat operating rod 66. The valve block 104 is reciprocately disposed as in the valve block 68. The ball 106 is similar in function and construction to the ball 82, while the ball 108 is similar in function and construction to the ball 76. The only difference in the two embodiments is in the shape of the notches 110 and 112, and the disposition of the springs 114 and 116. The springs 114 and 116 are carried in the notches 110 and 112 and the balls are allowed to slide upwardly and downwardly on the inner walls of the valve chamber. Accordingly, the balls seal the passageways 100 and 102 by being forced toward the passages rather than from the passages as disclosed in Figure 3. The springs 114 and 116 react on the valve block 104 rather than react on the casing as in the previously described modification.

Having described the invention, what is claimed as new is:

1. In an internal combustion engine which has a liquid cooling system and a charge forming device, an attachment for introducing selectively different grades of fuel into the charge forming device, said attachment comprising a case having a thermostat therein; a valve operatively connected with said thermostat, means forming a

liquid chamber in said casing and having said thermostat disposed therein, means connecting said chamber with the liquid cooling system of the engine, said case having two fuel passageways, said valve controlling said passageways, one of said passageways adapted to be connected with a quantity of fuel of one grade, the other passageway adapted to be connected with a quantity of fuel of another grade, said valve

being arranged so that when one of the passageways is open, the other passageway is closed, and a manually operable stem connected with said valve in order to retain said valve in a selected fixed position.

15. In an internal combustion engine which has a liquid cooling system and a charge forming device, an attachment for introducing selectively different grades of fuel into the charge forming device, said attachment comprising a case

20. having a thermostat therein, a valve operatively connected with said thermostat, means forming a liquid chamber in said casing and having said thermostat disposed therein, means connecting said chamber with the liquid cooling system of the engine, and a manually operable valve disposed in said casing for controlling the flow of engine coolant through said chamber.

25. In an engine which includes a cooling system and a charge forming device, means forming a by-pass for the cooling system, a casing disposed in said means and having a thermostat therein in communication with said means, a source of one grade of fuel and a source of another grade of fuel, means for conducting the fuel of each grade into said casing, a diaphragm separating said casing into a liquid chamber and

30. a fuel chamber with the thermostat in one chamber and the fuel conducting means communicating with the other chamber, and a valve arranged to control the flow of fuel through said fuel chamber operated by said thermostat.

35. The combination of claim 2 and said first-mentioned valve being arranged to control the different grades of fuel flowing through said case and including a valve stem with laterally opening notches therein, valve members located in said notches, means forming valve seats in said case for receiving said valve members, and means yieldingly opposing the movement of said valve members from said notches into said seats.

40. The combination of claim 2 and said case having two fuel inlet passageways and an outlet, a valve chamber communicating with said passageways and said outlet, said first-mentioned valve being located in said fuel chamber and arranged to control the passage of fuels through said passageways and including a valve core with laterally opening notches therein, and spring-loaded valve members located in said notches and arranged to seat in said passageways.
